Primary Examiner — Lauren R Calve(74) *Attorney, Agent, or Firm* — Foley & Lardner LLP(57) **CLAIM**

We claim the ornamental design for a handwheel with valve, as shown and described.

DESCRIPTION

FIG. 1 is a perspective view a handwheel;
 FIG. 2 is a front view thereof;
 FIG. 3 is a rear view thereof;
 FIG. 4 is a side view thereof;
 FIG. 5 is another side view thereof;
 FIG. 6 is a top view thereof; and,
 FIG. 7 is a bottom view thereof.

The ornamental design that is claimed is shown in the drawings as solid lines and surfaces having surface shading. The broken lines shown in the drawings depict environmental subject matter, are for illustrative purposes only, and form no part of the claimed design.
